NOTCHING MACHINE

Gjerlow G. Christensen, Hartford, Conn.

Application August 15, 1947, Serial No. 768,860

5 Claims. (Cl. 164—50)

1

This invention relates to a notching machine and more particularly to a machine for notching the corners of sheet metal blanks such as are used for conduits in air heating systems and the like.

An object of this invention is to provide a machine which will cut a notch in the corner portion of a blank and which is particularly suited for cutting such corners in blanks of elbows and the like, as well as for blanks of straight conduits.

Further objects and advantages of this invention will be more clearly understood from the following description and from the accompanying drawings, in which—

Fig. 1 is an elevational front view of a notching machine embodying my invention.

Fig. 2 is a plan view in section on line 2—2 of Fig. 1.

Fig. 3 is a view similar to Fig. 2, but showing a modification of the machine.

Fig. 4 is a plan view of a sheet metal blank for an elbow showing the notches formed by my improved machine.

Fig. 5 is a similar view showing a straight blank.

As shown in the drawings, my notching machine comprises a base 5 having a plurality of guide posts 6—6 thereon upon which is slidably mounted a punch plate 7 having attached sleeve bearings which is operated by means of a lever 8 that is pivoted on a post 9 and operates the said plate by a link 9—a.

A die 10 is mounted on the base 5. This die is flat in form and has a notch therein with cutting edges 11—11 which are relatively disposed to cut a notch in a blank of sheet metal with the edges of said notch relatively disposed at a desired angle.

The said die carries thereon a positioning bar 12 which is slidably secured upon the top surface of the die plate 10 and extends therefrom beyond the extremity of the said die plate. A supporting plate 13 is carried by said bar 12 in order to support a sheet metal blank in said machine.

The said die plate also carries a separate positioning bar 14 which extends at right angles to the bar 12, and which is also slidably mounted upon the surface of the die plate, as shown, preferably by means of a clamping screw 15 and guide slots 16—16 which retain the said bar in accurate relation to the cutting edges of the die.

A punch 17 is carried by the plate 7 and has cutting edges thereon in register with the cutting edges 11—11 of the die.

As shown in Fig. 4, a blank 18, for an elbow

conduit, is notched at 19—19 to permit the proper bending of the blank in constructing a conduit. In Fig. 5 there is shown a sheet of metal in the form of a blank 20 which is used for the sides of a straight conduit, and has the notches 21—21.

In order to permit cutting of the notches 19—19 in the corners of a blank for an elbow, such as 18, I provide a stop member 22 having a positioning point 23 which engages the curved edge 24 of the elbow blank to retain it in position under the punch 17 for cutting the notches 19—19. The said point 23, being close to the punch 17, permits its engagement with the edge of the blank close to the notch so that the curvature of said edge will not make a material difference in accurately positioning said blank for cutting the notches of the proper size. When it is desired to cut the said notches, the blank, indicated in dotted lines, is first placed against the positioning bar 12 and against the end of said point 23, thus bringing the corner portion of the blank in proper position under the punch 17 for cutting one of the notches 19. The blank may then be turned over so that the point 23 will engage the opposite edge and thereby permit positioning of the blank for cutting the opposite notch.

In cutting the notches in a straight blank such as 20, the positioning bars 12 and 14 may be arranged as illustrated in Fig. 3. The blank is then placed against the said bars, as shown in dotted lines, and the machine operated for cutting off the corner portions.

The surface of the die plate may be graduated, as at 25—26, to facilitate proper adjustment of the positioning bars for the different sizes of the notches which may be cut on said machine.

By providing the elongated positioning bars 12 and 14 which extend beyond the extremities of the die plate, I am able to reduce materially the size of said machine and still permit the cutting of notches in large blanks since the said blanks may be supported on the supporting plates 13 and 14—a as shown.

I claim:

45. 1. A notching machine of the character described comprising a base, a die plate mounted on said base, a positioning bar adjustably carried on said die plate and projecting therefrom, a supporting plate carried by the projecting portion 50 of said positioning bar for supporting a workpiece in position on said die plate, the said die plate having a corner portion thereof notched and provided with cutting edges, a punch plate slidably carried on said base, a punch on said punch plate, 55 and means for operating said punch in coopera-

tion with the cutting edges on the die plate for cutting notches in said work piece.

2. A notching machine of the character described comprising a base, a die plate mounted on said base, positioning bars slidably mounted and adjustable on the surface of said die plate, the said positioning bars projecting from the die plate, a supporting plate secured to each of said positioning bars exteriorly of the die plate and having the upper surface thereof coplanar with the surface of the die plate, cutting edges in said die plate, a punch cooperating with said cutting edges and carried on said base, and means for operating said punch.

3. A notching machine of the character described comprising a base, a die plate secured to said base, a notching portion having cutting edges in said die plate, a positioning bar adjustably slidable upon the surface of said plate and projecting therefrom, a supporting plate secured to said positioning bar exteriorly of said die plate and being movable therewith the upper surface of said plate being on a plane with the surface of said die plate, a punch movable relatively to said cutting edges, and means for operating said punch.

4. A notching machine of the character described comprising a base, a die plate carried on said base, a notching portion in said plate having cutting edges, a positioning bar extending from

said die plate, a supporting plate secured to said positioning bar exteriorly of the die plate having its upper surface on a plane with the plane of said die plate, and a guiding member on said die plate slidably adjustable relative to said cutting edges and having a projection adjacent to one side of said notch for positioning a blank relatively to the cutting notch by engagement with an edge portion of said blank close to said cutting notch.

5. A notching machine comprising a die plate having cutting edges, a positioning bar slidable on said die plate and extending therefrom in one direction and having a supporting plate secured thereto exteriorly of the die plate and co-planar therewith, a similar positioning bar extending from said die plate perpendicularly to the first of said bars, a punch, and means for operating said punch to co-operate with said cutting edges for a cutting operation.
